(57) **CLAIM**

The ornamental design for a fishing rod with surface ornamentation, as shown and described.

DESCRIPTION

The patent or application file contains at least one drawing executed in color. Copies of this patent or patent application publication with color drawings/photographs will be provided by the office upon request and payment of the necessary fee.

FIG. 1 is a side view of a fishing rod with surface ornamentation showing our new design in color;

FIG. 2 is a top plan view of a portion thereof;

FIG. 3 is a bottom plan view of a portion thereof;

FIG. 4 is a left side view of a portion thereof;

FIG. 5 is a right side view of a portion thereof;

FIG. 6 is a detail of the fishing rod with surface ornamentation illustrated in FIG. 1;

FIG. 7 is a side view of an alternative embodiment of a fishing rod with surface ornamentation showing our new design in black and white;

FIG. 8 is a top plan view of a portion thereof;

FIG. 9 is a bottom plan view of a portion thereof;

FIG. 10 is a left side view of a portion thereof;

FIG. 11 is a right side view of a portion thereof; and,

FIG. 12 is a detail of the fishing rod with surface ornamentation illustrated in FIG. 7.

Although the fishing rod is generally tapered as is conventional, such taper is not apparent in FIGS. 2-12, as the taper along the length of the rod is gradual, and the portions depicted in FIGS. 2-12 are relatively short.

The broken lines in the drawings are for illustrative purposes only and do not form a part of the claimed design.
